FOREIGN PATENT DOCUMENTS

WO D216757-001 * 10/2021

Primary Examiner — Marie D. Fast Horse

(57) **CLAIM**

The ornamental design for a self-service multi-function terminal as shown and described.

DESCRIPTION

1. Self-service multi-function terminal

1.1 : Bottom

1.2 : Top

1.3 : Back

1.4 : Right

1.5 : Front

1.6 : Left

1.7 : Perspective

Broken lines in the drawings represent features of the self-service multi-function terminal that form no part of the claimed design.
